CLAIM

The ornamental design for a trim piece for an automobile hood, as shown and described.

DESCRIPTION

FIG. 1 is a perspective view of our new design for a trim piece for an automobile hood;

FIG. 2 is a front elevation view thereof;

FIG. 3 is a rear elevation view thereof;

FIG. 4 is a top plan view thereof;

FIG. 5 is a bottom plan view thereof; and

FIG. 6 is a right side elevation view thereof, it being understood that the left side elevation view is substantially similar.

FIG. 1

FIG. 2

FIG. 3
